FUEL INJECTION PUMP

Desire J. Deschamps, Rutherford, and Douglas C. Clarke, Mountain Lakes, N. J., assignors to Deschamps Fuel Injection Corporation, New York, N. Y., a corporation of New York

Application September 23, 1943, Serial No. 503,470

7 Claims. (Cl. 183—173)

1

This invention relates to fuel injection pumps for internal combustion engines and has for its object the provision of an improved high pressure pump for injecting liquid fuel into the engine cylinders.

The operating speeds of such engines are constantly being increased and the invention aims to provide a fuel injection pump which is capable of satisfactory operation at the highest engine operating speeds without undue wear, without mechanical failure and which requires a small amount of power for its operation.

The pump of the present invention can be applied to Diesel (compression ignition) engines, and to Otto-cycle (spark ignition) engines using volatile fuel such as gasoline. When used in connection with the latter, the attaining of the correct air-fuel ratio is of great importance and it is an object of the invention to provide a pump capable of adjusting the quantity of fuel injected with unusual accuracy.

In applications to Otto-cycle engines operating with a volatile fuel and having the fuel-air ratio adjusted by means of an automatic mixture control mechanism it is desirable for the fuel pump to have as nearly as possible a straight line delivery curve, and it is an object of the invention to provide an injection pump having this characteristic, that is to say, wherein the output of the pump varies substantially directly with the engine speed for a given throttle setting.

With Diesel engines it is customary to employ a type of fuel injection pump which provides fixed timing of the beginning of the injection, the end of the injection period being varied in accordance with the power demands of the engine. Although this type of pump has many advantages when applied to aircraft Otto-cycle engines using volatile fuel, the general practice in this country still is to employ in connection with such engines a type of fuel injection pump which provides fixed timing of the ending of the injection, the beginning of the injection period being varied in accordance with the power requirements.

A further object of the present invention is to provide an injection pump construction which can, with the substitution of a minimum number of parts, be assembled in either of these forms or types. It is also an object of the invention to provide a fuel injection pump construction which is of such a nature that pumps can be readily changed over from one type to the other with the substitution of a minimum number of parts.

The invention will be understood from a consideration of the accompanying drawings which,

2

by way of example, illustrate one specific embodiment thereof together with a modification of one of its parts. In these drawings:

Fig. 1 is a vertical longitudinal section taken on the planes indicated by the broken line 1—1 of Fig. 2;

Fig. 2 is a vertical transverse section taken on broken line 2—2 of Fig. 1;

Fig. 3 is a vertical longitudinal sectional view of a single pumping unit drawn to an enlarged scale;

Fig. 4 is a fragmentary vertical section taken on the broken line 4—4 of Fig. 1 and drawn to the same scale as that figure;

Fig. 5 is a detail top view of the tappet construction shown at the left of Fig. 3 for actuating one of the plump plungers;

Fig. 6 is a view looking at the right hand end of Fig. 5;

Fig. 7 is a detail vertical section taken on line 7—7 of Fig. 3;

Fig. 8 is a detail vertical section taken on line 8—8 of Fig. 1;

Figs. 9—12 are vertical sectional views of the pump cylinder, plunger and output control sleeve illustrated at the right of Fig. 3 showing the plunger in various positions under the conditions of maximum pump output;

Figs. 13—16 are similar views under the condition of no pump output;

Fig. 17 is a diagram showing the movement of the plunger in relation to the angular movement of the pump shaft;

Fig. 18 is a view similar to the right hand portion of Fig. 3 illustrating a modified form of pump cylinder and plunger;

Fig. 19 is a fragmentary vertical section of certain parts shown in Fig. 1 shifted in their position for operation with the modified plunger and cylinder of Fig. 18;

Figs. 20—23, inclusive, are vertical sectional views of the pump cylinder, plunger and output control sleeve illustrated in Fig. 18, showing the plunger in various positions under the condition of maximum pump output; and

Figs. 24—27, inclusive, are similar views showing various positions of the plunger for the condition of no pump output.

Referring now to these drawings, and discussing first the general arrangement of the pump, it comprises three principal parts, namely, a drive housing 1, a central dividing wall or tappet housing 2, and a head 3 containing the pump cylinders, plungers, the control assembly and the outlet valves. The three sections are held together by means of a series of screws 4. The tappet housing 2 divides the pump as a whole

into two main compartments, a front compartment within the head 3 and a rear compartment within drive housing 1.

Drive housing 1 is provided with a mounting flange 5 by means of which the pump is attached to the usual mounting pad on the engine by a series of bolts or screws passing through holes provided in flange 5. In the rear compartment within drive housing 1 is mounted the pump shaft 6 which is splined at 7 at its outer end to provide a driving connection with the engine. Shaft 6 is mounted for rotation in its ball bearings 8 and 9, the former being mounted in the end wall of the driving housing 1 and the latter in a part fixed at the center of the tappet housing 2.

Within the pump there are provided a plurality of pumping units as illustrated in Fig. 3, each comprising a pump cylinder 10 (sometimes referred to as the cylinder barrel or bushing), a pump plunger 11, an output control member 12 and a plunger driving mechanism including a tappet structure indicated generally by numeral 13 and a slipper 14. These pumping units are arranged in a circular row at equal distances from the axis of pump shaft 6. In the embodiment illustrated in the drawings, twelve of these pumping units are shown, although any suitable number may be employed, and if the pump has more than about twelve cylinders it is desirable to arrange them in two concentric rows.

The pumping units are driven by means of a wobble plate 15, the operating face of which engages the slippers 14 of the several plunger driving mechanisms. Wobble plate 15 is angularly fixed with respect to pump shaft 6 and imparts a harmonic reciprocating motion to the respective plungers, the length of the plunger strokes being fixed or invariable. Wobble plate 15 is preferably arranged not to rotate with shaft 6, but merely to have its characteristic wobble motion imparted to it by the rotation of shaft 6 through the instrumentality of a thrust type ball bearing 16 angularly mounted on shaft 6. The wobble plate is restrained from rotation by its frictional engagement with slippers 14 and may consequently "creep" or rotate slowly.

The tappet structures 13 are slidably supported in tappet housing 2 in such a manner as substantially to prevent the passage of fluid in either direction through this housing or dividing wall 2. The details of this construction will be referred to later on. This enables the front compartment within head 3 to be utilized as an inlet reservoir for the fuel to be pumped and the rear compartment within drive housing 1 to be utilized as a collecting chamber for the lubricant for the tappets 13 which are supplied with pressure lubrication also to be described below.

The fuel is supplied to the interior of head 3 preferably by means of the usual transfer pump which delivers the fuel under a pressure usually of about 15 pounds. The fuel is delivered through an inlet connection 17 (Fig. 2), preferably through a filter element 18, and thence upwardly through a passageway 19 cored in the lower part of head portion 3 to the interior of the compartment within this head. This compartment is therefore filled with fuel at all times.

At the top of the head 3 there is preferably arranged a housing 20 having a vapor eliminator connection 21. Suitable passages 22 and 23 convey the vapor from the interior of head 3 to the interior of housing 20.

Referring now to Fig. 3, the cylinder chamber of each pumping unit is shown at 24 at the right

hand end of plunger 11. Plunger 11 is provided with an axial passageway 25 leading from the face of the plunger, that is, from chamber 24 inwardly beyond the end of cylinder 10. Communicating with axial passage 25 are an inlet passage 26 and a pressure relief passage 27. Each of these two passages includes a circular groove 28 in the surface of the plunger and cross passages 29 communicating with axial passage 25 as shown in Fig. 3.

Cylinder 10 and plunger 11 of Fig. 3 provide for fixed beginning of the injection period, the ending of the injection period being variable to regulate the amount of fuel injected.

The ending of the injection is controlled by the position of control sleeve 12, it being understood that this sleeve is shiftable along the surface of plunger 11. Inlet passage 26 coacts with the inner or left hand end of cylinder 10 to establish the beginning of the compression stroke or injection period and control member 12 is provided with a circular control edge at the right which cooperates with pressure relief passage 27 to terminate the compression or injection period as will be described in more detail presently.

The fuel in the compression chamber 24 is, during the compression stroke, forced out through the outlet valve 30 and flows through a longitudinal passage 31 to one of the outlet connections 32. These outlet connections, one for each pumping mechanism, are arranged around the periphery of tappet housing 2 as shown in Fig. 2. It will be understood that suitable tubing leads from these connections 32 to the injection nozzles of the respective engine cylinders in proper sequence corresponding with the firing order of the engine.

Valve 30 is held against its seat at the center of valve seat member 33 by means of a helical spring 34, the outer end of which engages a valve seat lock nut 35 which holds seat member 33 in position.

Pump cylinder 10 is made to have a close slip fit in its supporting aperture in the casting which forms the pump head 3, and is provided with a positioning flange 36 which engages a shoulder in head 3. The cylinder is held in place by the engagement of valve seat member 33 which is forced against the end of the cylinder by the valve seat lock nut 35.

This construction has the advantage that cylinders 10 can be readily removed and replaced with a modified form of cylinder such as shown in Fig. 18, should it be desired to convert or change over the pump to provide fixed timing of the ending of the injection period, with the output controlled by varying the beginning of the injection period. The construction also is advantageous from the standpoint of production in that the cylinder barrels or bushings 10 can be finish lapped before they are inserted in pump head 3, thus avoiding any lapping or touching up after assembly.

In Figs. 9-12, inclusive, various positions of pump plunger 11 in the cylinder 10 are shown with the control member 12 moved from the no output position of Fig. 3 to the right nearer the end of cylinder 10 in the position of maximum output. In Fig. 9 it is assumed that plunger 11 is at the extreme left hand end of its movement and is commencing a forward stroke toward the right. Fuel has flowed into the compression or working space 24 through inlet passage or port 26 and axial passageway 25 during the previous return stroke and will continue to do so as the plunger moves forward, until the left hand

edge of port 26 passes the left hand end of cylinder 10 as is shown in Fig. 10. This cuts off the inlet of the fuel to compression space 24, inasmuch as pressure relief port 27 is covered by output control sleeve 12, and causes the beginning of the injection period, that is, the beginning of the delivery of fuel through outlet valve 30.

The delivery of the compressed fuel continues until the right hand edge of pressure relief port 27 passes the right hand or control edge of output control member 12 as shown in Fig. 12. This places compression space 24 in communication with the fuel inlet reservoir in pump head 3 relieving the pressure on the fuel in the compression space, terminating the effective or delivery stroke and permitting outlet valve 30 to reseat itself. As the pump plunger 11 continues to the end of its forward movement, as shown in Fig. 12, the fuel continues to be forced back into the fuel inlet reservoir through relief port 27, as shown in Fig. 12.

During the return stroke of the plunger, fuel flows into the compression space 24 through inlet and relief ports 26 and 27 and passageway 25 under the transfer pump pressure. This is assisted also by the partial vacuum which is formed in the compression space during the period of closure of both the inlet and relief ports 26 and 27 as the plunger moves between the positions of Figs. 11 and 10, such vacuum exerting its influence after inlet port 26 opens and until it is reclosed on the next forward stroke of the plunger.

Referring now to Figs. 13-16, inclusive, output control member 12 has been assumed to be moved back to the no pump output position of Fig. 3. When the plunger has traveled forward or to the right and closed the inlet port 26, as shown in Fig. 14, pressure relief port 27 opens simultaneously, the right hand edge of this port passing the right hand edge of control member 12 at this instant. Consequently the pressure in compression space 24 is relieved at the same instant that the inlet port 26 is closed, and throughout the entire movement of plunger 11, as shown in Figs. 15 and 16, the fuel within compression space 24 continues to flow back through passage 25 and relief port 27 into the fuel inlet reservoir. Hence no fuel is delivered through outlet valve 30.

In Fig. 17, the motion of the plunger during a forward stroke is shown diagrammatically in relation to the angular movement of the pump shaft 6. At the 0° position of the pump shaft the forward motion of the plunger is assumed to commence, and corresponds to Fig. 9. From this point to the point A the motion of the plunger closes the inlet port 26, at which instant the injection period begins. This corresponds to Fig. 10. The injection period continues as the plunger advances from the point A to the point B which corresponds with Fig. 11 where the injection period ends for the maximum pump output. From the point B to the top of the diagram represents the period during which the relief port 27 is open.

It will be understood that as the output control sleeve 12 is shifted to the left from the position shown in Figs. 9-12, inclusive, the injection period will be correspondingly shortened, the point B on the diagram of Fig. 17 moving to the left approaching point A as the injection period becomes shorter and shorter.

In diagram 17 it will be seen that during the effective stroke of the pump, that is to say, during the time of injection, or, in other words, as the plunger is moving between the points A and

B, the motion of the plunger is near its maximum velocity and this velocity is also substantially constant since this portion of the sine curve, which represents the motion of the plunger under the action of the wobble plate, has a substantially constant slope.

Referring now to Figs. 1 and 2, the output control members 12 are shifted simultaneously to control the outputs of all of the pumping elements. This is accomplished by means of a disk 37 which is provided around its periphery with semicircular notches 38, the edges of which engage circular grooves 39 in the outer surfaces of output control members 12. Disk 37 is mounted for movement in the direction of its own axis to bring about this simultaneous adjustment.

For this purpose, disk 37 is fixed to or made integral with a cylindrical slide or plunger member 40 which is supported for longitudinal sliding movement in a circular aperture supported by the central dividing wall 2 opposite the end of pump shaft 6. Slide member 40 is biased to the right, as shown in Fig. 1, by means of a helical spring 41 and is moved to the left by means of a cam member 42 pinned to a cross shaft 43 and engaging a button 44 attached to the outer center of disk 37. Slide member 40, if desired, may be positively operated in both directions, avoiding the use of return spring 41.

In order to rigidly support shaft 43 in the interest of obtaining extreme accuracy of the movement of control disk 37, the shaft is provided with bearings 45 adjacent cam 42. Shaft 43 extends through the outside wall of the pump head 3, and preferably through both walls so as to permit a choice in the location of the pump control actuating lever 46 which is fixed to one of the projecting ends of the shaft. Packing glands 47 are provided to prevent the escape of fuel.

It will be understood that the pump capacity control lever 46 is actuated by the engine governor, or in case the pump is used on an engine having a fuel mixture control apparatus, then lever 46 is actuated by such apparatus.

It is of importance to accomplish the longitudinal shifting of the individual pump control members 12 on their respective plungers with the least possible friction and without the possibility of imparting a side pressure to the pump pistons 11 forcing or biasing them against the side walls of their respective cylinders 10. This is important not only in the interest of obtaining accurate output control but also in preventing wear of the plungers and pistons under the high speed at which the pump operates.

For this reason the notches 38 in the edge of the common control disk 37 are cut somewhat larger than the diameter of the bottoms of the grooves 39 in the control members 12 and the edges of these notches are maintained out of contact with the bottoms of these grooves, as shown in dotted lines in Fig. 2. This is done by means of a stationary pin 48 (Fig. 1) which is fixed in the central dividing wall 2 and extends parallel to the axis of disk 37. Pin 48 has a cylindrical portion which passes through an aperture in disk 37, with the walls of which it makes a close sliding fit. Furthermore at the periphery of disk 37 (Fig. 2) is provided a rim 37a raised above the surface of the web through which are cut the semicircular notches 38. This raised rim provides two narrow central surfaces at opposite sides of sleeves 12, avoiding binding between disk 37 and grooves 39 as might be the

case if there were a complete bearing all around the semicircular notches.

Referring now to the modification illustrated in Figs. 18-27, inclusive, there is here shown a construction of plunger and cylinder and output control mechanism which provides fixed ending of the period of fuel injection, the quantity of fuel injected being regulated by varying the beginning of the injection period. In this modification all the parts of the pumping unit are identical with that shown in Fig. 3 except the cylinder barrel or bushing 10a and the plunger 11a. That is to say, the tappet 13 and slipper 14 operate plunger 11a in the same manner in which they operate plunger 11; also the various members of the pump housing such as the drive housing 1, the tappet housing or dividing wall 2 and the head casting 3 and other parts of the pump are identical with those shown in Figs. 1-17, inclusive, although a change in the position of the control cam 42 is necessary as will be referred to below.

Referring particularly to Fig. 18, cylinder 10a is provided with a relief opening 48 which is spaced from its inner end. Plunger 11a is similar to plunger 11 in that it has a central axial passageway 25a but this passageway extends to a somewhat greater distance inwardly of the plunger than the passage 25 of plunger 11. Plunger 11a is also provided with inlet and relief passages but these are reversed in position with respect to inlet passages 26 and 27 of plunger 11 and are spaced a greater distance apart.

The inlet passage for plunger 11a is indicated by numeral 50 and cooperates with the left hand control edge of output control member 12, instead of the right hand control edge, and controls the beginning of the injection period instead of its ending. The relief passage of plunger 11a is indicated by numeral 51 and cooperates with relief outlet 49 in the walls of bushing 10a to fix the termination of the injection period. It will be understood that as in the case of plunger 11, the inlet and relief passages 50 and 51 are constructed to produce the quickest possible cut off and opening and for this reason embody the sharp edged circular grooves into which the cross passages from central passage 25a open, as illustrated in Fig. 18 and as previously described in connection with Fig. 3. It will also be understood that, like the construction of Fig. 3, the passages 25 and the cross passages are of large cross sectional area in relation to the volume of the compression space 24a in order to insure that this space is completely filled with liquid for each operating stroke and to aid in the ejection of vapor from this space so that the compression space at each stroke will be filled with "solid" liquid.

For similar reasons relief opening 48 in cylinder 10a comprises a continuous circular groove 52 cut in the interior surface of cylinder 10a and from this groove one or more small holes 53 open into the fuel inlet reservoir space within pump head 3 and surrounding the inner portions of cylinders 10a and plungers 11a. The inner control edge of groove 52 is a sharp circular edge to coact with a similar edge of the relief opening 51.

Referring now to Figs. 20-23, inclusive, the output control sleeve 12 is here shown in the position for maximum pump output and in Fig. 20 plunger 11a is beginning a forward or working stroke. The compression space 24a is in communication with the fuel inlet reservoir (the interior of pump head 3) through axial opening 25a and inlet

passage 50 and relief port 51. This communication continues until the left hand edge of passage 50 passes the left hand control edge of output control sleeve 12 and during this time a portion of the liquid which has filled compression space 24a on the previous back, or return stroke of the plunger 11a is forced out into the fuel reservoir together with any vapor bubbles which may be included with it. The liquid left in the compression space 24a is therefore "solid" liquid.

In Fig. 21 the plunger has advanced to the position just described and inlet opening 50 has been closed by control sleeve 12, and relief opening 51 remains closed by the walls of cylinder 10a. The injection period therefore begins at this point, the compressed fuel being forced out through the pressure operated outlet valve 38.

The injection period continues until the plunger has reached the position shown in Fig. 22 where the right hand or control edge of relief outlet 51 is just passing the left hand or control edge of the groove 52 of relief opening 49 which again places compression space 24a in communication with the inlet fuel reservoir, thereby relieving the pressure in the compression space and ending the injection period. Liquid from the compression space continues to be forced out through passages 50 and 49 until the plunger reaches the end of its movement which is shown in Fig. 23.

On the return or back stroke of the plunger this communication still persists until the right hand edge of relief opening 51 again reaches the position shown in Fig. 22 during which time fuel from the inlet supply reservoir again flows into the compression space 24a through the central passageway 25a. After the position of Fig. 22 is reached where this communication is cut off, a partial vacuum is formed in the compression chamber 24a as the plunger continues its back stroke to the position of Fig. 21 where this vacuum is broken by the passing of the left hand edge of inlet passage 50 beyond the left hand edge of control sleeve 12. At this point, the partial vacuum within the compression space is added to the pressure of the fuel within the head 3 produced by the transfer pump to cause the fuel to flow into the compression space 24a completely filling it. Then the plunger moves back to the position shown in Fig. 20 ready for a successive working stroke.

Now referring to Figs. 24-27, inclusive, the output control sleeve 12 has been moved to the right its maximum distance to the position of no pump output. Hence as the plunger commences its working stroke at the position shown in Fig. 24, as in the case of Fig. 20, the compression space 24a is in communication with the inlet fuel reservoir through the passage 25a and both the inlet passage 50 and the relief passage 51. Fuel (together with vapor, if any) is thereby forced out of the compression space through both passages until relief passage 51 is closed, and thereafter continues to flow out through the inlet passage 50, as shown in Fig. 25.

The plunger advances to the end of its working stroke without compressing the liquid in compression space 24a and hence without producing any outflow of fuel through the outlet valve 38 for the reason that, as shown in Fig. 26, control sleeve 12 is in such a position that the inlet opening 50 is maintained open right up to the instant where the relief passage 51 meets relief opening 49 in the cylinder. Afterwards, as shown in Fig. 27, the inlet opening is closed, but

the fuel continues to flow outwardly through relief passages 51 and 49 until the end of the outward stroke of the plunger is reached.

On the inward or back stroke of the plunger fuel again flows into compression space 24a, first through the relief openings 49 and 51 (Fig. 27) and afterwards through the inlet opening 52 as shown in Fig. 25, and finally through both the inlet opening 52 and relief opening 51, as shown in Fig. 24. This again fills the compression space 24a with liquid ready for another forward stroke of the plunger so that, should the sleeve 12 be shifted to the left from the no output position, the pump would be ready to deliver the amount of fuel corresponding to the position of sleeve 12.

In the comparison of Figs. 3 and 18, it will be seen that when the pump is arranged to provide fixed beginning and variable ending of the injection period, the no output position of output control sleeve 12 is at the left, whereas when the pump is arranged to provide a fixed ending and variable beginning of the injection period, the no output position of control sleeve 12 is at the right. Consequently in order that the rotation of output control shaft 43 may be in the same direction to produce the same effect, for example, to increase the output of the pump, it is necessary to change the angular position of cam 42 from the position shown in Fig. 1 to the position shown in Fig. 19, wherein the opposite operating edge or back of the cam coacts with button 44 to actuate the common control disk 37. This permits spring 41 to move disk 37 to the right so as to move control sleeve 12, adjacent the ends of cylinders 10a, to the proper position to produce zero output of the pump. Hence the rotation of the shaft 43 and cam 42 to increase the output of the pump is in the same direction as it is in Fig. 1, as shown by the arrows in these two figures.

In order to adjust the control edges of output control members 12 with respect to one another so as to obtain uniform delivery of fuel from each of the twelve pumping units, the construction shown in Figs. 3 and 7 is employed. Each of the output control members 12 comprises an inner member or sleeve proper 54 which is threaded into an outer or body member 55, in the surface of which groove 39 is cut for the engagement of the control disk 37. By turning sleeve 54 with respect to body member 55 the control edges of the sleeve are shifted longitudinally with respect to the body member.

The two parts are locked in adjusted position by means of a snap ring 56 having an inwardly projecting tongue 57. The left hand end of sleeve member 54 has a head in which a series of longitudinal equally spaced slots 58, for example, six in number, as shown in Fig. 7, are cut. The left hand portion of body member 55 is recessed to receive the slotted head of sleeve 54 and in the overlying wall of body 55 is a series of small holes 59 to receive the tongue 57 of snap ring 56 and allow it to project into one of the slots 58, thereby locking the two sleeve members against relative rotation. The number of holes 59 is preferably one more, or less, than the number of slots 58 in the embodiment illustrated, there being seven of these holes making it possible to adjust one part with respect to the other by only $\frac{1}{2}$ of a turn, thus providing a very close adjustment.

In order to provide for high speed operation without undue wear or mechanical failure and at minimum power consumption, and further to

facilitate accurate metering of the pump output, an important consideration is the avoiding of side loads on the pump plungers 11. This is obtained in the present pump construction, first, by utilizing the arrangement of inlet and relief ports for the pump cylinders 10 previously described which provides balanced hydraulic loads on the pump plungers, and, second, by removing mechanical side thrust from the individual pump plungers by providing an improved plunger driving mechanism. This mechanism includes an improved tappet construction and an improved slipper construction.

The avoidance of side thrust on the plungers, particularly when the pump is handling volatile fuel such as gasoline, is of particular importance inasmuch as the lubrication qualities of such liquid are substantially nil and it is impracticable to make provision for the supply of lubricant to the walls of the cylinder and plunger. Yet these surfaces must slide upon one another with an extremely close fit in order to prevent leakage at the high operating pressures of such pumps.

The tappet structure indicated generally by numeral 13 (Figs. 3, 5 and 6) comprises two telescoping members, a push rod 60 which is preferably made hollow, to reduce inertia forces and also to facilitate lubrication, as will appear later, and a thimble member 61 which affords a support for push rod member 60 and assists in coupling the tappet structure to the rear end of plunger 11. To prevent leakage of fuel to the left of division wall 2 or lubricant to the right, a packing ring 60a is provided near the end of push rod member 60 between its outer surface and the inner surface of thimble 61.

Thimble 61 slidably supports the tappet structure in an elongated guide bushing 62 which is fixed in the tappet housing 2, the two telescoping members 60 and 61 reciprocating together without relative movement under the action of wobble plate 15, which, as previously mentioned, engages slipper 14.

Slipper 14 is mounted on the left hand end of push rod member 61 which is provided with an enlarged head 63 in the outer surface of which is a socket 64 in which is seated the semispherical surface 65 of slipper 14. Slipper 14 comprises a segment of a sphere, that is to say, a section of a sphere whose height is less than the radius of the sphere. In other words, the distance from the center of socket 64 to the wobble plate is less than the radius of the sphere from which the interacting socket surfaces 65 and 64 are formed.

Hence the frictional contact of the face of slipper 14 with the face of wobble plate 15 which tends to prevent the wobble plate from turning, has a negligible tilting effect upon the slipper 60 about its pivoting point with respect to tappet member 61, this pivot point being the center of the sphere just referred to. Avoidance of such tilting effect insures that the face of the slipper throughout its periphery is at all times in contact with the wobble plate. This is important in preventing non-uniform wear on the slipper which would eventually effect the length of the plunger stroke and interfere with accurate metering.

Slipper 14 is held on tappet member 61 by a retaining member 66 which is fitted into a bore in the left hand end of member 60 and fixed thereto by a pin. As indicated in Fig. 3, member 66 is provided with a retaining head 67 connected therewith by a reduced neck portion 68, by means

of which the slipper is permitted freedom of oscillatory movement in its socket.

Guide bushing 62 is tightly fitted into its aperture in tappet housing 2 and the outer surface of tappet member 61 is also closely fitted to the interior of guide bushing 62, the clearance being only sufficient to permit lubrication and the reciprocating motion of the tappet in the guide and the fit being close enough to prevent leakage of fuel from the fuel reservoir within the pump head 3 past tappet housing 2 or the leakage of lubricant from the lubricant collecting reservoir at the left of tappet housing 2 into the fuel reservoir. Not only the close sliding fit of the tappet in the guide bushing prevents leakage of fuel past the tappet, but also the fact that the lubrication is done by a high viscosity oil (the engine oil) and at a pressure superior to that of the fuel pressure in the inlet reservoir.

Although guide bushings 62 are mounted in substantial alignment with the centers of cylinders 10, it is impracticable in production to obtain sufficient accuracy to eliminate the impartation of side thrust or binding action to the plungers 11 if the plungers and tappets are constructed as a single rigid member. Consequently in the present invention a self-aligning coupling between the tappet 13 and plungers 10 has been provided.

In order to provide such a coupling arrangement plunger 10 is provided at its inner end with a coupling knob 68 connected to the plungers by a neck portion 70 considerably smaller in diameter than the plunger. The end of push rod member 60 bears against the head of knob 68 and thimble member 61 extends beyond the end of push rod member 60 and is provided with a bayonet joint which engages the underside of knob 68.

This bayonet joint is formed by means of a T-shaped slot 71 (Fig. 5) in the side of thimble 61 which is adapted to receive the knob 68 and neck 70. The body portion 72 of this slot is slightly larger than neck 70 and the top part of the T-shaped slot 71 is slightly larger both in width and in height than the knob 68. The underside of knob 68 seats on the inner surface 73 of the end of thimble 61 which is displaced from the edges of T-shaped slot 71. This enables the tappet and plunger to be locked together during assembly which facilitates this work.

A plunger return spring 74 engages at its right end a shoulder on tappet guide bushing 62 and at its left hand end a flange 75 formed on the left end of thimble 61. Return spring 74, acting through thimble 61 and the inner surface of knob 68, forces the outer end of knob 68 against the end of push rod member 60 which in turn forces the socket surfaces 64 and 65 against one another and the face of slipper 14 against the face of wobble plate 15. Hence all reciprocating parts of the pumping unit are maintained in contact with one another, avoiding lost motion at any point under all conditions of operation of the pump.

However, a particularly important advantage of this arrangement is that damage to the pump is prevented in the event of the "sticking" of a plunger in its cylinder. In such an event due to the fact that push rod 60 and thimble 61 are in push-pull connection with the plunger, these two members and the slipper 14 are held out of the path of the wobble plate, thus preventing the slipper, push rod and thimble constituting the plunger driving mechanism, from being thrown

violently back and forth each time the wobble plate rotates. This could result in serious damage, rapidly putting the whole pump out of operation.

5 The tappet mechanisms and slippers 14 are provided with pressure lubrication, the oil being received from the lubrication system of the engine and entering the pump from the mounting pad through a drilled passage 76 (Fig. 1) in drive housing 1. From the right hand end of this passage the oil enters a groove 77 (Figs. 4 and 1) in the face of tappet housing or dividing wall 2. Thence a sloping inwardly directed passage 78 communicates with a circumferential groove 79 in the outer surface of guide bushing 62 for one of the lowermost pumping units (Fig. 4).

This groove not only serves to lubricate this particular pumping unit (as will be presently understood) but also serves to conduct oil to supply lubrication to all of the remaining pumping units, the oil flowing from the inner side of groove 78 through a drilled passage 80 to a central circular groove 81. Circular groove 81 is formed in the surface of a central bore extending through dividing wall 2 in which the support 40 for output control disk 37 and for shaft ball bearing 8 is fixed. From this circular groove 81, other passages 82 similar to passage 80 radiate and carry the lubricating oil to the remaining eleven pumping units, each of the guide bushings 62 having a circular groove 79 to receive the oil.

Referring now to Fig. 3, the oil from groove 78 in bushing 62 flows through a sloping hole 83 in bushing 62 which communicates with a groove 84 on the inner surface of bushing 62. During the reciprocation of the tappet 13 and at the inner end of each stroke a hole 85 in thimble 61 momentarily registers with groove 84 and permits a small amount of oil to be discharged through it into a groove 86 and a hole 87 through the wall of push rod 60. Groove 84 also serves to supply oil to lubricate the sliding of thimble 61 in bushing 62.

40 Oil from the interior of push rod 60 passes through a small groove 88 in retaining member 66 to lubricate the socket surfaces 64 and 65 of the slipper 14 and also to lubricate the coating surfaces of the slipper and wobble plate. Preferably one or more small passageways 89 are provided to allow the oil to escape from the interior of the slipper so as to prevent the building up of oil pressure within the slipper which would tend to separate the slipper from the surface of the wobble plate and interfere with accurate metering.

45 The pump is provided with a device for determining when some particular pumping unit (which may be designated as pumping unit No. 1) has its plunger 11 in position corresponding to the beginning or the ending of the injection period depending upon whether the pump is provided with the cylinders or plungers shown in Fig. 3 or those shown in Fig. 18. This device 50 comprises a timing pin 90 which is arranged to slide in a vertical aperture at the top of drive housing 1. The pin is normally held in withdrawn position by means of a helical spring 91 but may be pushed down with the finger to bring its inner end into engagement with a groove 70 92 (Fig. 8) formed in the peripheral surface of a timing disk 93 which is fixed to pump shaft 6 just inside of ball bearing 8. Both the end of pin 90 and the surface of groove 92 are so formed that the rotation of the shaft will force the pin 55 out of the groove if the spring should fail to

retract it. It will be understood that the position of groove 92 in timing disk 93 corresponds to the beginning (or the ending) of the injection period.

The foregoing is an exemplifying disclosure of the improved fuel injection pump of the present invention, it being understood that the invention, in either its spirit or scope, is not limited to the particular construction and arrangement of the various parts of the pump illustrated in this disclosure, but that various changes in the mechanical expression of the inventive ideas set forth in this disclosure can be made without departing from the spirit and scope of the invention, which are intended to be set forth in the appended claims.

We claim:

1. In a fuel injection pump, a cylinder, a plunger therein, rotary cam means to drive the plunger, and driving mechanism between the plunger and cam means including a tappet member, a guideway therefor substantially in axial alignment with said cylinder, said tappet member having a push-pull connection to the plunger, said tappet having a spring biasing it into engagement with the cam means, whereby, in the event of the sticking of the plunger in the cylinder said driving mechanism is held out of the path of the cam means.

2. In a fuel injection pump, a cylinder, a plunger therein, a wobble plate to drive the plunger, a support disposed between the cylinder and the wobble plate having an opening therein substantially in alignment with said cylinder, and driving mechanism between the plunger and wobble plate including a push rod coacting with the end of the plunger, a supporting member for the push rod slideable in said opening, said supporting member having a laterally yielding connection with said plunger, and a spring biasing said supporting member in a direction to maintain the end of the plunger in contact with the push rod and said driving mechanism in engagement with the wobble plate.

3. In a fuel injection pump, a cylinder, a plunger therein, a wobble plate to drive the plunger, driving mechanism between the plunger and wobble plate including a push rod coacting with the end of the plunger, a supporting member for the push rod having a push-pull self aligning connection with said plunger, a guideway for said supporting member substantially in axial alignment with said cylinder, and a spring biasing said supporting member in a direction to maintain the end of the plunger in contact with the push rod and said driving mechanism in engagement with the wobble plate, whereby, in the event of the sticking of the plunger in the cylinder, said driving mechanism is held out of the path of the wobble plate.

4. In a fuel injection pump, a cylinder, a plunger therein, a wobble plate to drive the plunger, a support disposed between the cylinder and the wobble plate having an opening therein substantially in alignment with the cylinder, and driving mechanism between the plunger and wobble plate including a push rod coacting with the end of the plunger, a supporting member for the push rod slideable in said opening, said supporting member having a self aligning connection with said plunger, and a spring biasing said supporting member in a direction to maintain the end of the plunger in contact with the push rod and said driving mechanism in engagement with the wobble plate.

5. In a fuel injection pump, a cylinder, a plunger therein having a knob at its driving end, a wobble plate to drive the plunger, and driving mechanism between the plunger and wobble plate including cooperating pushing and pulling members, said pushing member coacting with the outer surface of said knob and said pulling member with the inner surface thereof and a spring to actuate the plunger on its return stroke, said spring being arranged to act upon said pulling member to maintain the end of the knob in engagement with said pushing member and said pushing member in engagement with the wobble plate, whereby, in the event of the sticking of the plunger in the cylinder, said driving mechanism is held out of the path of the wobble plate.

6. In a fuel injection pump, a cylinder, a plunger therein having a knob at its driving end, a wobble plate to drive the plunger, and driving mechanism between the plunger and wobble plate including a pair of telescoping members, one engaging the outer surface and one engaging the inner surface of said knob and a spring to actuate the plunger on its return stroke, said spring being arranged to act upon the telescoping member which engages the inner surface of the knob, whereby, in the event of the sticking of the plunger in the cylinder, said driving mechanism is held out of the path of the wobble plate.

7. In a fuel injection pump, a cylinder, a plunger therein having a knob at its driving end, a wobble plate to drive the plunger, a support disposed between the cylinder and the wobble plate, said support having an opening therein substantially in alignment with said cylinder, and driving mechanism between the plunger and wobble plate including inner and outer telescoping members, said inner telescoping member serving as a push rod to engage the outer surface of said knob, said outer member sliding in said opening and making laterally movable engagement with the inner surface of said knob, and a spring to actuate the plunger on its return stroke, said spring being arranged to act upon the outer telescoping member.
